DIFFERENTIAL STAGE LIFT FLOW DEVICE,
BELLows TYPE

Alexander Boynton, San Antonio, Tex.

Application December 8, 1939, Serial No. 308,311

5 Claims. (Cl. 137—111)

My invention relates to stage lift flowing devices for wells, the flow being accomplished by the expansion force of air or gas.

The principal object is to start wells at relatively low pressures and to flow them at low pressures and low gas-oil ratios.

Other objects are: 1, to cause the valve employed to admit and cut off the supply of pressure fluid to seat with greater force and certainty than is now practiced in the art; 2, to automatically regulate the flow of pressure fluid in proportion to the volume thereof required to be employed to accomplish economical operation; and 3, to cause a well to flow through either the tubing or the casing by employing the same device for both purposes.

In carrying out these objects, I employ a pressure-responsive metallic bellows, anchored at one end and free at the other, within a chamber interposed between the pressure fluid and the upstanding well liquid in the eduction conduit. The free end of the bellows has attached to it two valves. Each valve in the devices, which are spaced at intervals in a tube within a tube, is adapted to close and cut off the flow of pressure fluid from the induction conduit into the eduction conduit at a pre-determined greater pressure existing within the induction conduit, irrespective of which conduit may be employed for induction or eduction.

I attain the foregoing objects by mechanism illustrated in the accompanying drawing, in which—

Fig. 1 is a broken side view, partly in section showing the devices in a well.

Fig. 2 is a longitudinal section through one of the flow devices.

Fig. 3 is a cross section on the line 3—3, Fig. 2.

Fig. 4 is a cross section on the line 4—4, Fig. 2.

Fig. 5 is a longitudinal section of a modified form of valve and seat.

Fig. 6 is a longitudinal section of another modified form of valve and seat.

Similar reference characters are employed to refer to similar parts throughout the several views.

The column of well liquid which pressure fluid causes to stand up above the depressed liquid level in either the annular space 1a or in the tubing 2, Fig. 1, will be referred to as the upstanding column.

The difference between the pressures obtaining within and without the tubing at any device will be referred to as the differential.

The conduit containing the pressure fluid,

whether it be the tubing or the casing, will be referred to as the induction tube; and the conduit through which the liquid is expelled from the well, whether it be the tubing or the casing, will be referred to as the eduction tube.

Flow of well liquid from the well will be caused by employing this invention for the introduction of pressure fluid into the upstanding column which will be elongated by the subsequent expansion of the pressure fluid so admitted.

In Fig. 2, the body 12, having the central longitudinal passage 12c of the same diameter and in line with the passage through the tubing, may be cast or otherwise formed integrally with the shell 12a, having the central longitudinal bore 12c between the sloping ends 12b and 12b'. Said bore houses a metallic bellows member 13 which has a stationary lower support 14.

The upper end of the bellows 13 is secured upon its connection 19 by the solder or weld 13a and the lower end of the bellows is secured upon its connection 14 by the solder or weld 13b.

The bellows, which may be of a diameter such as one to one and one-half inches, should have a clearance such as one thirty-second to one-sixteenth inch with the wall of the bore 12c.

The upper valve tube 23 and the lower valve tube 24 may be pressed into the central openings within the bushing 21 to which member they may be further secured by the welds 22 and 24b.

The bellows upper end connection 19 has the packing 20 within its upper end compressed by means of the threaded engagement between the members 19 and 21 in order to seal the bellows hermetically at that end.

The connection 14, having an annular flange landed upon the internal annular shoulder 12d, supports the bellows centrally of the bore 12c. Proximate the lower end of the shell 12a, the packing 15 produces a hermetic seal above the annular space 16c and the packing 17 produces a hermetic seal below this annular space. The packing 15 is urged upon the nether side of the flanged portion of the member 14 by the sleeve 16, having the packing 17 and the gland ring 17a closely engaged between it and the plug 18 by means of the threaded engagement of this plug within the lower end of the shell 12a. The sleeve 16 has slight clearance over the member 14, the lower portion of which has similar clearance within the plug 18.

The lower coiled spring 25 has slight clearance over the tube 24 and somewhat larger clearance within the bellows. The upper coiled spring 26 has large clearance with the tube 23 and small

clearance within the bore 12c. The lower spring 25 is installed under some compression between the members 14 and 18. The upper spring is installed under similar compression between the roof of the bore 12c and the bushing 21.

The upper valve 23a formed upon the upper end of section 23 of the tubular valve stem, is adapted to engage upon the seat 12j, and the lower valve 24a upon the lower section 24 of said stem is adapted to close upon the seat 14a. Both valves are normally open, as shown, until closed by the predetermined differential.

The arcuately tapered bores 12h and 14c have the annular passages 12m and 14e, respectively, between their walls and the untapered portions 15 of tubes 23 and 24, respectively.

The central circular passage 24c, extending from end to end of the tubes 23 and 24, may have a diameter such as $\frac{1}{8}$ to $\frac{3}{8}$ inch.

The upper end of the upper valve tube 23 has a close slide valve fit within the untapered portion a of the tapered bore 12h. The lower end of the lower valve tube 24 has a close slide valve fit within the untapered portion b of the bore 14c. These sleeve valves operative within the straight bores a and b, because of their close clearance, restrict the passage of fluid and prevent the valves 23a and 24a from being forced open by sudden dropping of slugs of liquid in the eduction tube.

The clearance between the tube 23 within the lower end of the upper tapered bore 12h and the clearance between the tube 24 within the tapered lower bore 14c at the openings 14b may be such as the equivalent of a circular opening having a diameter of $\frac{1}{8}$ to $\frac{3}{8}$ inch. The openings 12e, 16b, 14b and 12g may each have a diameter such as $\frac{1}{4}$ to $\frac{7}{8}$ inch, all dimensions depending, of course, upon the well conditions, such as depth, rate of flow, size of tubing, and physical properties of the liquid to be lifted.

Manifestly, a greater fluid pressure within the bellows than that contacting its exterior will tend to stretch the bellows and seat the valve 23a; while a greater fluid pressure contacting the exterior of the bellows than that inside of it will tend to compress the bellows and the spring 25 and thereby seat the lower valve 24a.

The pressure fluid exerts the valve closing force which is opposed by the weight of the well liquid and the force required to stretch or compress the bellows and the spring resistance, depending upon the direction of the pressure fluid flow. The force required to compress or stretch the bellows is constant. Likewise, the force required to compress either one of the springs may be constant. The force of the pressure fluid is constant at any given value thereof. The only force which varies according to the place where it is exerted is the weight or back pressure of the upstanding liquid column. This force actuates the valves.

In flowing through the tubing as the eduction conduit, the valve 23a should close at a pressure per square inch somewhat greater than the weight of the upstanding column manifested per square inch between adjacent devices, which may be spaced in the tubing at intervals of 150 to 300 feet. Such adjustment provides that the valve in an upper device will not close until the next lower device has been uncovered to intake pressure fluid. A similar adjustment and spacing of the devices in the tubing may be employed for flow through the casing, unless the volume of liquid to be discharged through the casing is great. In that event, a different adjustment may be made.

to admit more pressure fluid into the upstanding column.

The pressure fluid employed for flowing through either the tubing or the casing should 5 have a value somewhat greater than two to three times the differential force required to seat the valves. Manifestly, increasing the value of the pressure fluid will increase the rate of liquid flow from the well.

10 In flowing through the tubing, the path of the pressure fluid through the device will be out of the annular space 1a, Fig. 1, into the tubing passage 12c', Fig. 2, via the opening 12g, the chamber 12j, the annular passage 12m, the passage 24c, the annular passage 14e, the openings 14b, the inner annular chamber 16a, the openings 16b, the outer annular chamber 16c, and the internal opening 12e, in the order named.

In flowing through the casing, the path of the pressure fluid is the reverse of that stated for flowing through the tubing.

In flowing through the tubing, the force which compresses the bellows and the spring 25 to seat the valve 24a at a pre-determined differential, is exerted exterior of the bellows, this force acting in the bore 12c through the opening 12g. The opposed force urging the valve 24a away from its seat is the resistance of the upstanding column of well liquid in the tubing exerted interiorly of the bellows acting through the opening 12e, the annular chamber 16c, the openings 16b, the annular chamber 16a, the openings 14b, and the annular space 14e, in the order stated, plus the force exerted by the bellows and the spring 25.

30 In flowing through the casing, the force which stretches the bellows and compresses the spring 26 to seat the valve 23a at a pre-determined differential is exerted interiorly of the bellows, this force acting through the opening 12e, the outer annular chamber 16c, the openings 16b, the inner annular chamber 16a, the openings 14b, and the annular passage 14e, in the order named.

35 The opposed force urging the valve 23a away from its seat is the resistance of the upstanding column of liquid in the annular space 1a, Fig. 1, exerted exteriorly of the bellows through the opening 12g and the chamber 12f, Fig. 2, plus the expansive force of the spring 26.

40 It will be observed that the clearance between the lower end of the tube 24 and the tapered bore 14c increases as the valve 23a approaches its seat 12j, while, at the same time, the clearance between the upper end of the tube 23 and the tapered bore 12h is decreasing. Manifestly, these 45 clearances become reversed if the valve movement is reversed. These tapered bores 12h and 14c, co-acting with the straight tubes 23 and 24, throttle the pressure fluid admitted into the upstanding column so as to permit, or tend to 50 permit, the greatest flow thereof when either of these valves are approximately half way of their travel. Both bores 12h and 14c may be straight, however, or one may be straight and the other tapered so as to meter the pressure fluid as may 55 be desired for different well conditions.

55 Since the annular space 1a is usually much greater than the size of the tubing, greater volume of pressure fluid often will be required to flow the well through the casing. To provide 60 such greater volume of pressure fluid, the clearance between the valve tube 23 and the bore 12h may be increased or the spring 26 may be made stronger, thereby increasing the differential required to close the valve 23a.

65 Ordinarily, the tubing flow is to be preferred

to the casing flow, on account of less frictional resistance in the tubing, but means for flowing through the casing is often valuable in cleaning out the wells; after which tubing flow can be resumed quickly if the flowing devices are adapted to flow through either the tubing or the casing.

Since the diameter of the bellows is many times greater than the diameter of the tubes 23 and 24, as shown, it is evident that much greater force will be imparted to the valves than would result from employing the usual valve seated by the differential force acting upon the same area as that of the valves.

The installation plan in Fig. 1 will be employed to illustrate flowing either through the tubing or the casing. In employing Fig. 1 to illustrate the tubing flow, it will be assumed that the flow line 4a is closed at the casing head.

A hermetic seal is formed between the casing 1 and the tubing 2 by the casing head 4, proximately above the ground surface 3. The devices 12 are spaced at proper intervals in the tubing 2 by means of the couplings 2a and the female end 12n of the flow devices.

In the upper regions of the well, the tubing may be enlarged, the swaged nipple 5 being employed to connect the different sizes of tubing. The extension line 2b may lead to a production tank.

The anchor string 7 may extend to the bottom of the well 9, this string and the tubing being joined together by the nipple 6, having openings 6a communicating between the interior of the tubing and the annular space 1a.

The contents of the formation 10 may enter the well through gun perforations 11. The liquid level in the casing and tubing is assumed to be at A.

Now, to flow the well through the tubing, turn pressure fluid of proper value out of the pipeline 3 into the annular space 1a, it being assumed that the flow line 2b is open. The pressure in the space 1a will quickly close the valves 24a of the devices. The liquid in the casing will become depressed to B and will rise in the tubing to C. The upstanding column, therefore, will extend up the tubing from D to C. The device next to the base of the upstanding column will open its valve 24a in response to the low differential obtaining there. The corresponding valve in the second device above the base at the upstanding column either will remain closed or be partially open, depending, of course, upon the spacing of the devices and the predetermined force required to close the valve 24a and upon the weight of the upstanding column above that device.

The depressed liquid level B will continue to lower if the rate of liquid flow from the well is greater than the inflow. If this occurs, the lower devices will be uncovered, in turn, and the well, thus, will flow by stages from progressively lower levels as the flowing operation continues, uncovering one device after another, until the lateral openings 6a in the nipple 6 are reached by the pressure fluid, which will then expel the upstanding column as a slug.

It will be noted that the valves are always open at a pre-determined distance above the base of the upstanding column and that they close successively as the base of that column moves downward.

Now, to flow the well through the annular space 1a, i. e. using the casing as the eduction tube, the pipe line 3 will be disconnected and replaced by a plug in the casing head. The pipe line 2b will

become the induction tube for pressure fluid and the discharge of well liquid will be through the pipeline 4a.

The larger size tubing shown in the upper portion of the well and the swaged nipple 5, preferably, will be replaced with tubing of the smaller size if the well is to be flowed through the casing other than during short periods for clean-out purposes only.

It being assumed that the well liquid in both casing and tubing is standing at A when the pressure fluid is turned into the tubing 2 from the pipeline 2b, the devices will quickly close their valves 23a as the pressure builds up in the tubing. At the same time the liquid in the tubing will be depressed to D and will upstand in the annular space 1a at E. The device next above the base of the upstanding column will open and discharge pressure fluid into that column.

The action of the devices in flowing the well through the casing is so similar to that stated for the tubing flow that the operation will be understood without further explanation.

In Fig. 5, it is shown that the valve 24d may be convex, the seat 14d being formed to engage this valve, while the bore 14c is uniformly tapered.

In Fig. 6, it is shown that the valve 24d' may be concave to engage the seat 14d', the bore 14c' being uniformly tapered as in Fig. 5.

It will be understood that the valves in the same device may be adjusted to close at the same differential or different differentials by employing springs of different forces, and that these forces may be made to vary progressively with increasing depth as well conditions may require. It will be understood, also, that the volume of pressure fluid introduced into the upstanding column can be varied by either changing the spacing of the devices or by employing pressure fluid of higher or lower value.

It has been proved that pressure fluid is more efficient at low values; and it is evident that lower pressures can be employed to flow a well by stages, as herein explained, than could be employed to expel the well liquid from the eduction tube by a force that would have to overbalance the entire unaerated upstanding column.

The foregoing specification, drawing, and appended claims are intended to set forth the invention as fully as may be done within the limits of a patent, with the understanding that many minor changes can be made in the construction and arrangement of parts within the scope and purpose of the stated objects and allowed claims.

What is claimed is:

1. In a device for flowing wells, a valve body, a housing on said body, said housing having a cylindrical inner chamber with a fluid inlet at the upper end from the exterior of the valve body and a fluid outlet at the lower end communicating with the interior of said body, upper and lower valve seats in said housing, a tubular valve stem having upper and lower valves thereon adjacent said seats, and means on said stem anchored to said housing and responsive to differential fluid pressures inside and outside said body to move said stem and said valves, said means closing the passage of fluid through said housing except by way of the tubular valve stem.

2. In a device for flowing wells, a valve body having a fluid opening therein, including a housing on said body at said opening, said housing having a cylindrical inner chamber with a fluid inlet at the upper end and a fluid outlet at the

lower end communicating with the fluid opening in said body, upper and lower valve seats in said housing, a tubular valve stem having upper and lower valves thereon adjacent said seats, a bellows diaphragm in said housing, a support for said diaphragm having a sealing connection with the lower end thereof, a bushing closing the upper end of said diaphragm about said valve stem, and springs above and below said bushing, said tubular valve stem furnishing a fluid passage through said housing.

3. In a device for flowing wells, a valve body having an opening therein, a housing on said body having an upper port leading to the exterior of the housing, a lower port therein communicating with said opening, valve seats at the upper and lower ends of said housing, a tubular valve stem between said seats, valves at the upper and lower ends of said stem, said stem forming a fluid passage, a diaphragm on said stem closing passage of fluid through said housing except through said stem, said diaphragm being responsive to fluid pressures inside and outside the same to move said stem and said valves.

4. In a device for flowing wells, a valve body having an opening, a housing on said body having an upper port communicating with the exterior of the body and a lower port communicat-

ing with said opening, a bellows diaphragm having its interior open, to said lower port, a bushing having sealing connection with the upper end of said diaphragm, a valve stem comprising upper and lower sections mounted in said bushing, a passage through said valve stem sections and said bushing for fluid, valve seats for the upper and lower ends of said stem, said valve stem being movable by differential pressures upon said diaphragm toward one seat and away from the other depending upon fluid pressures inside and outside said body.

5. A valve body including a housing having therein an upper port, a lower port therein communicating with the interior of the body, a lower valve seat in said housing, an upper valve seat, a cylindrical tubular valve stem between said seats, tapered valves at each end of said stem, said valve stem forming a fluid passage between said ports, and means responsive to fluid pressure sealing the passage of fluid through said housing except by way of said valve stem, said valve seats having a cylindrical area adjacent thereto and a tapered area outside said cylindrical area whereby the fluid may be metered as said valve approaches said seats.

ALEXANDER BOYNTON.
